SLIDE RULE

Addison W. Learned III, and Rosalie C. Learned, both of 88 Dorset Road, Holliston, Mass. 01746

Filed Sept. 2, 1969, Ser. No. 18,962

Term of patent 14 years

Int. Cl. D10—99

U.S. Cl. D52—6

FIG. 2.

FIG. 1.

FIG. 3.

FIG. 1 is a front view of slide rule in the closed position, showing our new design;

FIG. 2 is a front view of the slide rule with the slide extended; and

FIG. 3 is a cross sectional view taken along the line 3—3 of FIG. 1.

The undisclosed rear of the slide rule is a mirror image of the front and shown in the figures.

The broken lines are shown for purposes of illustration only.

I claim:

The ornamental design for a slide rule, substantially as shown and described.
